Primary Examiner — Jack Reickel*Assistant Examiner* — Salamah Jordan(57) **CLAIM**

The ornamental design for an abdominal workout machine, as shown and described.

DESCRIPTION

FIG. 1 is a front, left, top perspective view of an abdominal workout machine showing my new design;

FIG. 2 is a back, right, bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the bounded area 9 of FIG. 1;

FIG. 10 is an enlarged view of the bounded area 10 of FIG. 2; and,

FIG. 11 is an enlarged view of the bounded area 11 of FIG. 8.

The broken lines shown on the drawings depict portions of the abdominal workout machine that form no part of the claimed design. The dot-dash lines depict the enlarged view boundaries that do not form part of the claimed design.

1 Claim, 11 Drawing Sheets(56)
